UNITED STATES PATENT OFFICE.

ARISTIDE LAVERDIERE, OF GILBERTVILLE, MASSACHUSETTS.

LOOM-SHUTTLE.

1,276,084.

Specification of Letters Patent. Patented Aug. 20, 1918.

Application filed January 31, 1916. Serial No. 75,324.

To all whom it may concern:

Be it known that I, ARISTIDE LAVERDIERE, a citizen of the United States of America, residing at Gilbertville, in the county of 5 Worcester and State of Massachusetts, have invented certain new and useful Improvements in Loom-Shuttles, of which the following is a specification.

This invention relates to improvements in 10 loom shuttles, and provides an eye and tension for the weft or filling, the construction of the parts being such that the invention may be readily applied to loom shuttles and to shuttles of like character by merely 15 enlarging the aperture for the usual eye of the shuttle.

The object of my improvement is to provide a shuttle tension in which the weft engaging member or presser and its spring 20 will be housed within a cylindrical body portion that is located in a bore formed in the shuttle, the presser and its spring being associated so that the spring will bear against one of the walls of a recess in the 25 body portion to move the presser against an opposite wall of the recess, as will be hereinafter set forth.

In the accompanying drawings which illustrate a preferred form of my invention, 30 Figure 1, is a plan view of a portion of a loom shuttle showing the tension device applied thereto. Fig. 2, is a side elevation. Fig. 3, is a section on the line 3—3 of Fig. 1. Fig. 4, is a longitudinal section of the 35 tension device detached. Fig. 5, is a side elevation, partly in section, and in this view a portion of the casing for the body portion of the tension device is broken away. Fig. 6, is a sectional view on the line 6—6 of 40 Fig. 4. Fig. 7, is an inverted plan view of the presser block or member. Fig. 8, is an end view. Fig. 9, is an end view of the presser block, and Fig. 10, is an end view 45 partly in section of a modification of the presser block.

Referring to the drawings, the shuttle 11 is provided through one side with an aperture or bore 12 which extends from the outer side of the shuttle into a cavity 50 formed in the shuttle, such bore being cylindrical and of a size to receive the tension device, the shuttle is also provided with a smaller bore or opening 13 that is located opposite the center of the bore 12, the purpose of the opening being to admit of the

insertion of a punch or like implement used to force the tension device out of the bore 12, when it may be desired to remove the tension device from the shuttle, either for the purpose of expanding the spring or for 60 smoothing the weft or thread engaging surface of the presser block.

The body portion of the tension device comprises a cylindrical member 14, which between its ends is provided with a recess or opening that provides a chamber 15, for the presser block and its spring, the member 14 is bored longitudinally to provide thread or weft eyes, the ends of the way for the thread 16 being rounded or countersunk to 65 avoid sharp edges, and it will be noted that the thread passage 16 is out of line or eccentric with the longitudinal axis of the cylindrical member 14, and by so positioning the thread passage I provide a range of adjustment that is sufficient to locate the eye in alignment with the side recess 17 of the shuttle. The locating of the opening or thread passage eccentric to the longitudinal axis of the cylindrical member 14 is desirable as in 70 practice the bore 12, in fitting my tension device to old shuttles may be slightly out of line with the side recess. The length of the body portion or member 14 is such that one 75 end will extend through the wall of the shuttle, as shown by Fig. 1, to position the inner end of the tension device in line with the center of the bobbin and to admit of access to a screw that secures a casing to the member 14, which screw also indicates the 80 position of the presser. 85

The cylindrical member 14 is preferably made of hard metal, porcelain or other suitable material, and has an aperture for a screw 18 that connects a casing 19 to the member 14. The casing or cover 19 is made of comparatively soft metal as brass or copper and not only insures a tight fit in the bore of the shuttle in which the tension device is placed but such cover also serves 90 to close the chamber for the presser block and its spring to prevent displacement thereof, when the tension device is marketed as an article of manufacture, separate from the shuttle. 95 100

The presser block 20 may be provided on its upper side with a centrally located boss 21 the circumference of which has a recess 105 to receive the lower portion of a spring 22, and instead of having a projecting boss a 110

recess 21' may be formed in the presser block, either the boss or the recess will maintain the spring in engagement with the central portion of the presser plate. The underside of the presser plate 20 is shaped to provide concave portions 23, a centrally located transverse portion 24 which is flat and shoulders 25 which are on the same plane as the transverse portion 24, the 10 shoulders 25 prevent rocking of the presser plate upon the flat surface of the bottom wall of the chamber 15 against which the presser block is forced by the spring 22. When the presser block and its spring are 15 placed in the chamber the spring will be compressed and one end of the spring will engage the upper wall of the chamber.

In practice the diameter of the casing for the body portion will be substantially the 20 same as the exterior of the "eye" that is supplied for shuttles, that are usually provided in the way for the thread or yarn with a "filling brush" and my improvement takes the place of the "filling brush" and 25 the ordinary "eye", and my improvement may be used with a "filling brush", particularly when it is desired to either oil or moisten the filling thread or yarn.

The shuttle tension hereinbefore described 30 may be cheaply manufactured, the spring and the presser block may be removed from the body portion so that the spring can be expanded to give the requisite pressure of the presser block toward the flat surface of the chamber and upon the thread. When 35 the parts are separated the presser block and the flat wall of the chamber may be smoothed by filing or grinding to obliterate any groove or grooves that may be formed 40 therein by the passage of the thread. The convex portions of the presser block assist in admitting the tool or hook that is usually used in threading the tension device, and in use the tension device will hold the weft 45 or filling taut and prevent kinking while weaving, and the fibers on the weft or filling will be laid as the same is drawn between the presser block and the wall of the body portion.

50 The design of the presser block may be

varied, particularly as to the configuration of its face which engages the filling, and I prefer to locate the chamber in the body portion to one side of the center of the body portion, the cover may have a rough 55 exterior or it may be screw threaded, in order to positively engage the bore in the shuttle.

I claim.

1. A tension device for loom shuttles, 60 comprising a cylindrical body member having throughout its entire length a longitudinal bore which is intersected by an open sided transverse chamber that has one of the walls thereof on the same plane as the 65 thread engaging portion of the longitudinal bore, a presser-block maintained entirely within the chamber and having in line with the longitudinal bore a flat centrally located thread engaging portion one end of which is 70 curved, means on the opposite side of the presser block from its thread engaging face for attaching thereto one end of a coiled spring, a coiled spring attached to the presser block and engaging with one of the 75 walls of the chamber, and a casing which encompasses the body member.

2. A tension device for loom shuttles, comprising a cylindrical body-member having a longitudinal bore which is intersected 80 by a transverse open sided chamber one of the walls of said chamber being in line with a portion of the longitudinal bore, a presser-block maintained within the chamber and having a flat centrally located thread en- 85 gaging portion; curved ends and side shoulders, and a coiled spring attached to the presser-block said spring engaging one of the walls of the chamber.

3. A tension device for loom shuttles comprising a cylindrical body-portion having a longitudinally and eccentrically positioned bore, and an intermediate transverse chamber one of the walls of which is on a line 90 with the longitudinal bore, a presser-block 95 having in line with the bore intermediate convex portions, a coiled spring attached to the presser block and engaging with one of the walls of the chamber.

ARISTIDE LAVERDIERE.
